UNITED STATES PATENT OFFICE

GUSTAVE C. ABERLE, OF GLENSIDE, PENNSYLVANIA

DESIGN FOR A STOCKING

Application filed July 29, 1931. Serial No. 40,712. Term of patent 3½ years.

To all whom it may concern:

Be it known that I, GUSTAVE C. ABERLE, a citizen of the United States, residing at Glenside, county of Montgomery, and State of Pennsylvania, have invented a new, original, and ornamental Design for Stocking, of which the following is a specification, reference being had to the accompanying drawings, forming part thereof.

I claim:

The ornamental design for a stocking as shown and described.

GUSTAVE C. ABERLE.
